UNITED STATES PATENT OFFICE.

WILKIE TINKER, OF ANAMOOSE, NORTH DAKOTA.

TANK-HEATER.

1,322,973.

Specification of Letters Patent. Patented Nov. 25, 1919.

Application filed May 10, 1919. Serial No. 296,185.

To all whom it may concern:

Be it known that I, WILKIE TINKER, a citizen of the United States, and a resident of Anamoose, in the county of McHenry, 5 State of North Dakota, have invented certain new and useful Improvements in Tank-Heaters, of which the following is a specification.

My invention is an improvement in tank 10 heaters, and has for its object to provide a device of the character specified for use in preventing the freezing of water in tanks, which may be partly submerged in the 15 water in the tank and which will burn while so submerged, and which may be fed with fuel while so submerged.

In the drawings:

Figure 1 is a perspective view of the improved heater; 20 Fig. 2 is a longitudinal vertical section; Fig. 3 is a horizontal section; Fig. 4 is a section on the line 4—4 of Fig. 3.

The present embodiment of the invention 25 is shown arranged within a tank 1, the heater being partially submerged in the water, as shown, and resting upon the bottom of the water tank.

The improved heater comprises a casing 30 3 of substantially cylindrical form, having three extensions 4, 5 and 6, respectively, the said extensions being approximately rectangular in cross section. The main body 3 is separated from the extension 4 by a partition 4^a fastened securely to the casing 3 at 35 its opposite side edges by means of rivets as shown, its bottom, as indicated at 5^a, being cut away to form an ash door, and a grate 6^a is arranged transversely of the casing 3, 40 the shaking handle 7 of the grate extending into the extension 4.

This grate is mounted to oscillate on supporting lugs 8, and may be oscillated by 45 lifting the cover 10, which is provided for normally closing the top of the extension 4, the said door being hinged to upstanding lugs 11 on the wall of the extension and it has a flange 12 fitting within the upper end of the extension.

50 This door has a damper opening which may be closed by a damper 13, the said damper being pivoted to the door and slidable thereon and having a handle for manipulating the same. The inner edge of this door 55 10 abuts against the partition 4^a and a cover 14 is provided for covering the top of the

casing 3. This cover 14 is in two parts, as shown, the body portion 14 covering the top of the casing 3 while the rear portion 14^a has extensions 15 and 16 which cover the tops of the extensions 5 and 6. Thus the body portion 14 of the cover may be removed without disturbing the portion 14^a. The extensions 5 and 6 are connected at their bottoms by a cross trunk or casing 17 and a draft pipe 18 extends upwardly from a smoke box 19 arranged within the casing 3, the partition 20 having a nipple about which the draft pipe engages.

A transverse partition 20 is provided in 70 the casing at the top of the smoke box, the said partition closing also the tops of the extensions 5 and 6. The draft pipe 18 extends from an opening in the partition 20 at the smoke box, and the partition 20 has a 75 feed opening in its top, a cover 21 being provided for closing the opening. This cover 21 as also the cover 14 have handles for convenience in operating the same. The smoke box 19 is open at its bottom and at its 80 rear wall as shown in Fig. 4, the opening at the rear wall opening into the extension 5, and the said opening is adapted to be closed by a gate or damper 22 which is hinged to the partition 26 to swing into position to 85 close either the open bottom of the smoke box or the open rear wall, that is, the communication between the smoke box and the extension 5.

The damper is operated by means of a 90 sliding rod 23 which is mounted to slide in a guide 24 and in the partition 20, and the rod is connected to the gate or damper by a link 25. When the rod is moved upwardly from the position of Fig. 4 the gate or 95 damper will be swung into position to close communication between the smoke box and the extension 5, while when the rod is swung downwardly the gate or damper will be swung to close the open bottom of the 100 smoke box. Thus a direct or indirect draft is provided.

When the gate or damper 22 is swung upwardly the heated air may pass directly from the combustion chamber into the smoke 105 box and through the flue to the atmosphere. When the damper is swung downwardly to close the lower end of the smoke box the heated air must pass through the upper end of the partition 27 into the extension 6 110 which opens near the said upper end into the casing 3, down the said extension and

through the trunk 17 to the lower end of the extension 5, and thence upwardly in the extension 5 into the smoke box.

The dividing walls between the extensions 5 and 6 and the main body 3 are formed by partitions 26 and 27, which are mounted to slide in guides 28 on the walls of the casing 3. Thus either of the said partition walls 26 or 27 may be withdrawn. The partition wall 27 has an opening at its top for placing the extension 6 in communication with the casing 3, while the partition 26 has an opening at its top for placing the extension 5 in communication with the smoke box.

Referring to Figs. 1 and 3, it will be noticed that at its bottom the casing 3 and the extension 4 have outwardly extending lugs 30 provided with openings by means of which the heater may be secured to the bottom of the tank. The fuel is fed through the door 21, the cover 14 being first lifted, and the ashes may be removed through the compartment 4 by lifting the cover 10. The amount of air needed may be supplied by the damper 13. Two lugs 31 are set about midway of the partition 4^a for the purpose of guiding the poker to the opening in the grate. In shaking the grate, the cover 10 is laid back upon the cover 14, and the poker may be passed down in the extension 4 between the lugs 31 into the socket in the grate 6^a for the purpose of shaking the same.

I claim:

1. A tank heater comprising a casing having a pair of vertically extending chambers spaced apart from each other and extending from the top to the bottom of the casing and separated from the casing by the partitions

detachably connected with the casing, said 40 chambers communicating at the bottom of the casing, and one of the chambers communicating with the casing near its top, a smoke box near the top of the other chamber with which said chamber communicates, 45 a draft pipe leading from the smoke box, said smoke box having an open bottom, and a damper arranged within the smoke box and adapted to close the bottom or to close the communication between the smoke box 50 and the top of the adjacent chamber.

2. A tank heater comprising a casing having a pair of vertically extending chambers spaced apart from each other and extending from the top to the bottom of the 55 casing, said chambers communicating at the bottom of the casing, and one of the chambers communicating with the casing near its top, a smoke box at the top of the other chamber with which said chamber communicates, 60 a draft pipe leading from the smoke box, said smoke box having an open bottom, and a damper arranged within the smoke box and adapted to close the bottom or to close the communication between the smoke 65 box and the top of the adjacent chamber.

3. A tank heater comprising a casing having a pair of vertically extending chambers spaced apart from each other and extending from the top to the bottom of the casing, 70 said chambers communicating at the bottom of the casing, and one of the chambers communicating with the casing near its top, a smoke box at the top of the other chamber, and communicating therewith and with the 75 casing, and means for alternately closing the communication.

WILKIE TINKER.
